US0D1015303S

(12) **United States Design Patent** (10) **Patent No.:** **US D1,015,303 S**
(45) **Date of Patent:** **** Feb. 20, 2024**

(54) **CONFERENCE SPEAKER**

- (71) Applicant: **LUXSHARE PRECISION INDUSTRY CO., LTD.**, Shenzhen (CN)
- (72) Inventors: **Yun Feng**, Shenzhen (CN); **Guoqin Huang**, Shenzhen (CN); **Yong Huang**, Shenzhen (CN)
- (73) Assignee: **LUXSHARE PRECISION INDUSTRY CO., LTD.**, Shenzhen (CN)

(**) Term: **15 Years**

(21) Appl. No.: **29/821,181**

(22) Filed: **Dec. 28, 2021**

(30) **Foreign Application Priority Data**

- Jul. 26, 2021 (CN) 202130476457.0
- (51) LOC (14) Cl. 14-01

(57) **CLAIM**

The ornamental design for a conference speaker, as shown and described.

DESCRIPTION

FIG. 1 is a first perspective view of a conference speaker and camera embodying my new design;

FIG. 2 is a second perspective view thereof;

FIG. 3 is a third perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged view of the selected portion 10 in FIG. 1.

The broken lines shown in the figures depict portions of the conference speaker that form no part of the claimed design.

1 Claim, 10 Drawing Sheets
